UNITED STATES PATENT OFFICE.

WILLIAM E. HALE, OF FORT WASHINGTON, PENNSYLVANIA, ASSIGNOR TO R. H. BEAUMONT CO., OF PHILADELPHIA, PENNSYLVANIA, A CORPORATION OF PENNSYLVANIA.

SKIP-HOIST SYSTEM.

Application filed February 7, 1925. Serial No. 7,509.

My invention relates to material handling apparatus, and especially systems employing a loader for a hoisting bucket, such as skip-hoist systems now widely used for handling coal, sand, gravel, etc., etc. In general, such a loader comprises a movable part or structure that delivers the material from a source of supply into the bucket when the latter is in position ready to receive it, and shuts off or prevents the discharge at other times. It is the object of my present invention to provide for normally securing a movable loader in inactive position, so as to obviate risk of accidental discharge of material, or other such inconvenience.

In the drawings, Fig. I illustrates the application of my invention to a material handling system, which is here shown in side elevation.

Fig. II is a view similar to Fig. I, with some of the parts in different positions.

Figs. III and IV are detail sectional views taken as indicated respectively by the lines 25 III-III and IV-IV in Fig. I.

In these illustrations, the source of supply of material is shown as a hopper 1 with an inclined outlet 2 at its bottom. The discharge controlling loader 3 shown is hung 30 from the outlet 2. The loader 3 is swingable up and down about a horizontal axis 4, but normally occupies the inactive position shown in Fig. I, where it closes or prevents discharge from the outlet 2. Counterweights 5 substantially or approximately 35 counterbalance the discharge chute portion 6 of the loader 3, while any material remaining therein from previous activity of said loader may even help to swing the same upward and keep it in its inactive elevated position, as shown in Fig. I. The bucket 7 served by the loader 3 is shown as a wheeled skip bucket, and its track 8 is shown as inclined adjacent the loader. The loader 3 is swung down into active position when the bucket 7 reaches or approaches loading position, as shown in Fig. II, and is swung up into inactive position again when the bucket rises, being (preferably and as here 50 shown) actuated or operated both ways by the bucket itself. When the bucket 7 descends, a lower corner or flange projection 9 of the bucket engages a swinging hook device 10 pivotally suspended from the spout

6, in the path of the bucket, and thus pulls 55 the loader down; when the bucket 7 rises, its upper edge engages the lower side of the chute 7 and thus swings the loader upward. As shown, the hook device 10 is equipped 60 with cushioning springs 11, which permit 65 it to yield and thus ease the shock when the descending bucket strikes the hook,—as set forth in U. S. Patent No. 1,411,831, to Beaumont, granted April 4, 1922. The general operation of a loader and bucket combination such as here illustrated is described 70 in this patent and in U. S. Patent No. 1,359,212, to Webster, granted Nov. 16, 1920.

The means here shown for normally securing the loader 3 in inactive position is 75 in the nature of an automatic latch device, comprising one or more members 12 pivoted at 13 to suitable supporting means, such as lugs or ears 14 on the hopper 1. As shown in Figs. I, II, and III, there are latch members 75 12, 12 at both sides of the loader chute 6, in the form of angle bars arranged with flanges 15 upward and outward, and they are interconnected by a cross-bar 16 rigidly secured to said flanges 15. These members 80 12, 12 are shouldered at 17 (as by notching of their lower flanges) to engage or hook over projections or lugs 18 on the chute 6 (in the form of angle-bar clips) when the chute 6 swings upward to its inactive position shown in Fig. I. In order that the latches 12, 12 may remain in the position shown in Fig. II when said latches are disengaged and the chute 6 swung downward,—ready to be lifted by the lugs 18, 18 as the 90 chute returns and thus reengage the lugs automatically,—these latches 12, 12 may be sustained by means of stop projections 20, 20 fast to their upper ends, and normally resting (or nearly so) against the hopper 1. 95 As shown, the upper and lower ends of the latch members 12, 12 are bent apart somewhat, while their intermediate notched portions lie close to the sides of the chute 6.

The latch device 12 may be automatically 100 operated or actuated to release the loader 3 for actuation by the bucket 7 when the latter approaches loading position, and it is advantageous to effect this by the action of the bucket itself. For this purpose, the hook device 10 may be provided with an arm portion 19 adapted to engage and trip the latch 12, by lifting shoulder 17 clear of lug 18.

This action is indicated in Fig. I, where the bucket corner 9 has struck the hook 10 and swung its upward extension 19 to the right, against the device 12, ready to lift the latter free as the bucket 7 continues its descent to engage and actuate the hook 10. Release of the loader securing means or lock 12 by a part of the loader operating device 10 affords the advantage of minimizing chances of derangement or accident: i. e., release will not occur unless the bucket 7 is in train to operate the loader 3 and receive the material discharged therefrom in consequence of such actuation.

Having thus described my invention, I claim:

1. In a system of the character described, the combination with a skip bucket and a cooperating loader, of gravity-influenced interconnected members serving to normally lock the loader positively against lateral displacement in inactive position but automatically actuatable to release the same when the bucket approaches loading position.
2. In a system of the character described, the combination with a skip bucket, a loader, and operating means for the loader actuated by the descending bucket, of a gravity-influenced latch-device comprising spaced members interconnected by a cross-bar for normally locking the loader in inactive position but releasable by said operating means when actuated by the bucket.
3. In a system of the character described,

the combination with a skip bucket and a 35 cooperating loader, of a gravity-influenced latch-device comprising interconnected angle bars having shoulders co-operative with lugs on the loader for automatically locking the same in inactive position, and means for 40 automatically tripping said locking means to release the loader for actuation by the descending bucket.

4. In a system of the character described, the combination with a skip bucket and a 45 cooperating loader, of a gravity-influenced latch comprising opposed angle bars with their ends bent apart and their intermediate portions shouldered to engage lugs on the loader for normally locking the same in in- 50 active position, and means actuated by the descending bucket for tripping the latch to release the loader.

5. In a system of the character described, the combination with a skip bucket and a 55 loader, of a gravity-influenced latch comprising opposingly directed angle bars with their ends bent apart and their intermediate portions shouldered to engage lugs on the loader for locking the same in inactive position, and an actuating hook for the loader in the path of the descending bucket, swing- 60 able by the latter to trip the latch and release the loader.

In testimony whereof, I have hereunto signed my name at Philadelphia, Pennsylvania this 3rd day of February, 1925.

WILLIAM E. HALE.
